ADJUSTABLE WINDOW SCREEN

Salomon Kafini Mahlouf, Montreal, Quebec, Canada, assignor of twenty-five percent to Frank C. Tenzer, Ste. Agathe des Monts, Quebec, Canada

Application January 7, 1952, Serial No. 265,263

15 Claims. (Cl. 160—21)

This invention relates to a window screen construction and more particularly to improvements in window screens of the laterally and vertically adjustable type.

A particular object of the invention is to provide durable top and bottom screen frames and housings of a novel construction between which screening is attached for vertical adjustment, said screening, frames and housings being laterally adjustable to fit windows of different widths.

Another object is to provide a novel interlocking arrangement between the upper frames and the lower housings respectively for telescopic adjustment of the frames and of the housings relative to one another.

A further object is to provide a locking means at opposite ends of the frames and housings for securing the frames to the housings against separation when the assembly is in its closed up condition. This is particularly desirable when the screens are being handled during transportation or when not in use, as it affords protection to the screening as well as the frames and housings, which otherwise might be destroyed or damaged during handling.

A still further object is to provide an adjustable screen, the component parts of which may be made of relatively light, durable and inexpensive materials such as plastic, and/or aluminum, die-cast material, rolled sheet material and the like.

Other objects and characteristic features of this invention will become more readily apparent from the following detailed description taken in connection with the accompanying drawings, in which:

Fig. 1 is a perspective view of a screen embodying this invention, shown in its closed position.

Fig. 2 is an elevational view of a screen, showing it secured to a window frame and sash.

Fig. 3 is a plan view of the lower housing frames taken along the section lines 3—3 of Fig. 2.

Fig. 4 is a view of the housings shown in Fig. 3 which have been separated and arranged in perspective for viewing the top walls and adjacent inner side walls in detail.

Fig. 5 is a sectional view of one of the housings taken along the section lines 5—5 of Fig. 4.

Fig. 6 is a vertical sectional view taken along the lines 6—6 of Fig. 2.

Fig. 7 is a vertical sectional view, enlarged, taken along the lines 7—7 of Fig. 2.

Fig. 8 is an end view of the screen construction.

Figure 9 is a longitudinal sectional view taken along the lines 9—9 of Figure 14.

Fig. 10 is a view in perspective of one end of a housing and the abutting inner surface of its removable end wall.

Fig. 11 is a bottom plan view of the upper frames taken along the section lines 11—11 of Fig. 2.

Fig. 12 is an enlarged top plan view partly broken and partly in section of the frames shown in Fig. 11 which have been removed from the sash frame for the sake of clarity.

Fig. 13 is a detail perspective view partly in section,

2

of a portion of one of the upper frames shown in Fig. 12.

Fig. 14 is a sectional view taken along the section lines 14—14 of Fig. 12.

Fig. 15 is a broken detail view of an opposite end of each upper frame showing them in relation to the corresponding end of each lower housing frame.

Fig. 16 is a detail view of one end of an upper frame, being the adjacent end of the companion to one of the frames shown in Fig. 15.

10 Fig. 17 is an exploded view in perspective of a modified housing assembly, certain parts being broken away and certain parts removed for clarification.

Fig. 18 is a perspective view of one end of a modified upper frame assembly which, with the component parts of the assembly shown in Fig. 17, constitute a complete screen assembly.

15 Fig. 19 is a perspective view of one end of the assembly shown in Fig. 17 showing certain parts in assembled relation and showing the upper frame assembly of Fig. 18 in section to indicate their relative positions in the overall assembly.

20 Fig. 20 is a vertical sectional view through one of the housings of Fig. 17 as it would appear in assembled relation.

25 Fig. 21 is an exploded view in perspective of one of a further modified housing assembly, certain parts being broken away for sake of clarity.

Fig. 22 is a perspective view of one end of a further modification of the upper frame assembly.

30 Fig. 23 is a fragmentary view of the inner bottom corner of an "inboard" cap shown in Fig. 21.

Fig. 24 is a sectional view taken along the lines 24—24 of Fig. 21.

35 Fig. 25 is a fragmentary view of a detail of the "inboard" and "outboard" caps shown in Fig. 21.

Fig. 26 is a fragmentary view in perspective, illustrating a modification of the assembly shown in Fig. 21.

Fig. 27 is a fragmentary view of the inner bottom corner of an "inboard" cap shown in Fig. 26.

40 Fig. 28 is a sectional view taken along the lines 28—28 of Fig. 26.

Fig. 29 is a view similar to Fig. 28 but showing a modified interlocking arrangement.

Fig. 30 is a fragmentary view similar to Fig. 26 but illustrating a further modification in the assembly.

45 Fig. 31 is a sectional view illustrating a further modified form of an upper frame assembly.

Fig. 32 is a fragmentary view of the inner bottom corner of an "inboard" cap shown in Fig. 30.

50 Fig. 33 is a sectional view taken along the lines 33—33 of Fig. 30.

Fig. 34 is a perspective view of one end of a still further modified housing assembly, certain parts being broken away for clarity.

55 Fig. 35 is a sectional view showing a still further modified form of upper frame assembly.

Referring more particularly to the drawings, 5 generally indicates a two-way adjustable screen including a pair of upper frames 6 and 7 of plastic or other light, durable material, slidably relative to one another for lateral adjustment of the screen and a pair of lower housings 8 and 9 also of plastic or other light, durable material, laterally slidably relative to one another in cooperation with the upper frames. A pair of flexible screening strips 10 and 11 are disposed in face-to-face relation, strip 10 being secured at its upper and lower edges between frame 6 and housing 8 and strip 11 being secured at its upper and lower edges between frame 7 and housing 9. Each screening strip 10 and 11 is slidably relative to one another with the respective frame and housing to which it is secured for lateral adjustment of the screen.

70 Referring more particularly to Figs. 12, 13, 14 and 16,

upper frames 6 and 7 are of a hollow structure and are arranged side by side with the side openings of the hollow interiors 12 and 13 in face-to-face relation. Frames 6 and 7 are united along their adjacent sides by an interlocking dovetailing arrangement (see Figs. 12 and 14) above the hollow interiors 12 and 13. This interlocking arrangement comprises dove-tail grooves 14 and 15 extending the full length of frames 6 and 7, respectively, and dove-tail projections 16 and 17 carried by frames 6 and 7 respectively. Dove-tail projections 16 and 17 are arranged at opposite ends of frames 6 and 7 with the projection 16 dove-tail fitted for sliding movement in groove 15 of frame 7 and projection 17 dove-tail fitted for sliding movement in groove 14 of frame 6. Each dove-tail projection extends from one end of its respective frame for a predetermined distance toward the mid-section of the frame so that, when the frames are slid relative to one another in opposite directions for lateral extension, the inner ends of the dove-tail projections will serve as abutments to prevent further extension of the frames beyond a predetermined point.

As seen in Figs. 11, 12, 13 and 14, each frame is hollow from the end remote from the dove-tail extension to a predetermined point in its length indicated at 18 and 19 respectively, substantially adjacent the inner end of the dove-tail extension, and may be solid for the remainder of its length. Rods 20 and 21 extending throughout the length of the hollow portions of frames 6 and 7 respectively are mounted in end walls 22 and 23 remote from the dove-tail extensions and in the inner end of the solid portions where the dove-tail extensions are located. Screening strip 10 is secured at its upper end to rod 20 of frame 6 while strip 11 is secured to rod 21 of frame 7. The bottom walls 24 and 25 of frames 6 and 7 are recessed along their inner edges, as indicated at 26 and 27, throughout the length of the hollow sections to provide clearance between the overlapping portions of screening strips 10 and 11. This clearance should be only sufficient to avoid frictional contact of strips 10 and 11 with each other during lateral extension of the screen.

Channel shaped spring clamps 28 and 29 are dove-tail fitted in corresponding, transverse slots 30 and 31 in the upper side of frames 6 and 7 in wedging engagement. These clamps are adapted to be clipped to the under side of the lower sash 32 of a window frame.

The lower housings 8 and 9, as seen in Figs. 3, 4 and 5, are of a hollow construction throughout their length. These housings are arranged side-by-side and are united along their adjacent sides by an interlocking dove-tailing arrangement (see Fig. 7) similar to that of the frames 6 and 7. This interlocking arrangement comprises dove-tail grooves 33 and 34 extending the full length of the inner side walls 35 and 36 of housings 8 and 9 adjacent the base thereof, and dove-tail projections 37 and 38 carried by housings 8 and 9 respectively. Dove-tail projections 37 and 38 are arranged at opposite ends of housings 8 and 9 with the projection 37 dove-tail fitted for sliding movement in groove 34 of housing 9 and projection 38 dove-tail fitted for sliding movement in groove 33. Each dove-tail projection extends from the end of its respective housing for a predetermined distance comparable to the corresponding projection of frames 6 and 7. When housings 8 and 9 are moved relative to one another in opposite directions in cooperation with frames 6 and 7 for lateral extension of the screen, the inner ends of dove-tail projections 37 and 38 will serve as abutments limiting the extension of the housings in the same manner as the projections of frames 6 and 7.

Housings 8 and 9 are provided at opposite ends with chambers 39 and 40 (see Figs. 3, 5 and 7). These chambers are located at the ends of the housings which carry the dove-tail projections and are closed at their outer ends. Spring rollers 41 (see Fig. 7), including a spring

41a helically coiled about a shaft 42 and secured at one end thereto, an end abutment 43 to which the other end of spring 41a is secured and a spring housing 44 fitted thereover in engagement with abutment 43, are inserted in the open inner ends of chambers 39 and 40 and are secured under tension for reeling and unreeling by the spring roller trunnions 45 which are fitted in key slots 46 provided in the side walls of the chambers.

Shafts 42 project from the free end of rollers 41 to 10 rotate therewith and extend throughout the remainder of the length of housings 8 and 9 and are secured at their outer ends in the end walls 47 and 48 respectively of the housings. That portion of each housing beyond chambers 39 and 40 is hollowed to provide an inner wall 15 surface which is oval in cross-section, as indicated at 49 and 50, the depth being greater than the breadth.

As seen in Figs. 4, 6 and 7, side openings 51 and 52 are provided in the upper half of adjacent inner side walls 35 and 36 of the housings 8 and 9. The screening strips 10 and 11 extend through the side openings 51 and 52 and are secured at their lower ends to shafts 42 to be wound therearound through the action of spring rollers 41. The top walls 53 and 54 of housings 8 and 9 are recessed along their inner edges, as indicated at 55 and 56 to provide clearance between the overlapping portions of screening strips 10 and 11. This clearance should be sufficient to permit lateral adjustment of the screen without frictional contact of the overlapping screening strips 10 and 11 but care should be taken to avoid gapping 30 between the screening strips.

End walls 47 and 48 of housings 8 and 9 are removable (see Fig. 10) for inserting the spring rollers 40 and shafts 42 with the screening attached thereto. End wall 48 is recessed in its inner surface, as indicated at 58, to conform with the cross-section of the inner wall surface 50. The wall 48 is provided with top and side flanges 59 and 60 which overlap top and side walls 54 and 61 of housing 9 when fitted thereon. A central opening 62 in the recessed portion of end wall 48 serves as a bearing surface for the outer end of shaft 42. Studs 63 and 64 on the inner surface of wall 48 are received in complementary openings 65 and 66 of housing 9 for centering the end wall with respect to the end of housing 9. Parallel upper and lower locking pins 67 and 68 extend through openings 69 and 70 in the top and side flanges 59 and 60 respectively and engage aligned recesses 71 and 72 in said housing, pin 68 also underlying stud 64 in a recess 73 provided therefor in the under side of stud 64.

The end wall 48 is provided with a lateral extension 50 74 having a central opening 75 for the reception of a complementary projection 76 (Fig. 5) on the adjacent end of housing 8. The outer marginal portion of extension 74 is bent rearwardly, outwardly and then forwardly to form a spring clip 77 which is fastened about the sash guide rail 78 (Fig. 3) of the window frame adjacent the sill. A dove-tail groove 79 on the top of end wall 48 overlying the recessed portion 58 of the end wall receives the adjacent end 23 of frame 7 which has complementary dove-tail flanges 80 (Fig. 16) on the side walls adjacent the bottom thereof. An abutment 81 on top of extension 74 which is undercut on the inner surface, serves as an end stop to frame 6. As seen in Fig. 15, frame 6 has a notch 82 on its end into which abutment 81 is recessed when the screen is in its closed up condition.

End wall 47 is of substantially the same construction as end wall 48. As seen in Figs. 3 and 4, it is provided with a recessed inner surface (not shown) corresponding to recess 58 of end wall 48 and conforming 70 with the contour 49 of the inner wall surface of housing 8. Top and side flanges 85 and 86 overlap the upper and outer side walls 53 and 87 of housing 8 when the end wall is fitted thereon. Opening 88 in housing 8 (see Fig. 5) provides a bearing for roller shaft 42 and 75 studs corresponding to the studs 63 and 64 of end wall

48 are fitted in complementary openings in the end of the housing. The end wall is locked in place by pins (not shown) in a similar manner to that set forth in connection with end wall 48. A lateral extension 89 has a central opening 90 for the reception of a complementary projection 91 on the adjacent end of housing 9. Instead of having a spring clip at the outer end of the lateral extension of the end wall, as shown in connection with end wall 48, the end wall 47 has its spring clip 92 integrally connected to side flange 86 to extend rearwardly, outwardly and then forwardly therefrom to be spring clipped about window frame rail 93. With this arrangement it will be seen that spring clips 77 and 92 are on the same side of the screen. A dove-tail groove 93, similar to groove 79, is provided for the reception of the end 22 of frame 6 which has complementary dove-tail flanges. As seen in Fig. 15, abutment 94, similar to abutment 81, serves as a stop member for the adjacent end of frame 7 which is notched at 96, in a similar manner to the notch 82 on the opposite end of frame 6.

For transportation and storage purposes the screen is telescoped in the manner shown in Fig. 1, with the window clamps 28 and 29 removed. In this position the end projection 91 is fitted in central opening 90 of the extension 89 of end wall 47 and the housings 8 and 9 are butted against the inner surface of said extension. The end 22 of frame 6 is dove-tail fitted in groove 93 in locking engagement to prevent vertical separation of the frame and housing. Also the adjacent end of frame 7 is butted against abutment 94. Similarly, end projection 76 is fitted in central opening 75 of the extension 74. Frame 7 is dove-tail fitted at its end 23 in the groove 79 provided therefor on end wall 48 and the adjacent end of frame 6 is butted against the undercut abutment 81.

To set the screen up in its operative condition, the housings 8 and 9 are extended slightly to remove projections 76 and 91 from engagement with end wall extensions 74 and 89 respectively and also to separate the ends 22 and 23 of frames 6 and 7 from their locking engagement in the grooves 79 and 93. The screen is then set upon a window sill (see Fig. 2) and the screens are laterally extended until guide rail clips 77 and 92 are spring clipped about the guide rails in the side frame of the window. Frames 6 and 7 are then placed in abutment with the under surface of the bottom frame of a window sash and clamps 28 and 29 are spring fastened to said bottom frame. The screen is now in its operative position and will expand or contract in the vertical direction to the limit of the screening length with raising and lowering of the window sash.

In Figs. 17 to 20, I have illustrated a modified form of screen assembly which includes upper frame members 100 and 101, housings 102 and 103 formed by extrusion of plastic or metals and moulded or die-cast end or cap members 104 and 105.

As shown in Fig. 18, upper frame members 100 and 101 are provided with a central longitudinally extending channel 106 and a restricted groove 107 in the upper surface communicating with channel 106. U-shaped holding clips 108, for gripping the lower edge of a bottom sash, are provided with a pair of retaining studs 109 fitted for sliding movement in channels 106 with the shank portion of the studs projecting through grooves 107. A stud 110, screw threaded through an opening in one arm of clip 108, engages one side of the sash frame to retain the clip in position. Frame member 100 has a T-shaped tongue projection 109a along one side which is slidably fitted in a complementary side channel in frame member 101 for longitudinal sliding movement of one frame member relative to the other. The under side of frame members 100 and 101 are slotted, as indicated at 111, adjacent their meeting edges, to receive the upper ends of the screens therein. The screens are retained in slots 111 either by compressing tongues 112 there-

against, or in the case of a plastic material the screen may be sealed in the slot by an adhesive or by the application of heat to the plastic around the slot.

As shown in Fig. 17, the screen housings 102 and 103 are hollow throughout their length and present top, bottom and one side wall 115, 116 and 117 respectively. Top wall 115 has its free side edge 118, slightly in rear of the corresponding side edge of the bottom wall 116 so that when the housings 102 and 103 are disposed in side-by-side relation, there will be sufficient room for the screens to pass freely therebetween. The bottom walls 116 of each housing are provided with an upwardly projecting member 119 adjacent the free side edge which has a longitudinally extending bayonet slot 120 opening into the outer side face. The inner wall of member 119 is tapered as indicated at 121 to permit free winding of the screen about a mandrel within the housing. When the housings are disposed in side-by-side relation the side openings of each bayonet slot 120 will be positioned opposite one another to receive locking members, herein-after described, for retaining the housings in face-to-face engagement for longitudinal sliding movement of the one housing relative to the other.

As will be seen particularly in Fig. 20 each screen 123 is wound about a mandrel 124 having its inner end connected at 125 to one end of a coil spring 126 contained in a spring housing 127. Mandrel 124 is fixed to rotate with spring housing 127 in any suitable manner. The screens are arranged so that the spring housing 127 is at one end of screen housing 102 and at the opposite end of screen housing 103.

As shown in Figs. 17 and 20, one end of each screen housing 102 and 103 containing the spring housing 127 is provided with an end or cap member 104, which, for the sake of brevity, I have termed an "inboard" cap. Cap 104 comprises a substantially rectangular outer wall 129 provided on its inner surface with a central trunnion 130 over which the outer end of spring housing 127 is fitted to rotate thereabout. A bottom and two top projections 131, 132 and 133, respectively, on the inner surface of outer wall 129 are shaped on their inner surfaces to conform with the outer surface of spring housing 127 so as to overlap the outer surface of spring housing 127 when the latter is fitted over trunnion 130. The outer side surfaces of projections 131, 132 and 133 are shaped to provide shoulders for inner surface portions of screen housings 102 or 103 so that one end of each of said housings will overlap the shoulders of said projections when the "inboard" cap is fitted to the end of the screen housing. It will be noted that the shoulders of these projections are inwardly offset from the marginal edges of the outer wall 129 so that the outer surfaces of the screen housing will be flush with the marginal edges of the "inboard" cap. The "inboard" cap may be locked to the end of screen housings 102 and 103 respectively by any suitable means, such as pins 134 extending through the walls of the screen housing and into suitable holes in any of the projections 131, 132, or 133.

The free end of spring 126 is fitted in a slot, as indicated at 135, in a spring winding pin 136 which projects through "inboard" cap 104 and trunnion 130. The outer end of pin 136 has a slotted, enlarged head 137 which is received in a deepened recess 138 in the outer surface of the cap. A cotter pin 139 adjacent the spring retaining end of pin 136 is also receivable in a recess 140 in trunnion 130. When the spring 126 is attached to pin 136 it normally pushes the pin so that the cotter pin 139 recedes into recess 140 and the head 137 is flush with the outer surface of cap 104. To increase the tension on spring 126 a suitable tool is fitted in the slotted head 137 and the pin 136 is moved inwardly until the cotter pin 139 is free of recess 140. When suitable tension has been applied by turning pin 136, the pin is pushed outwardly by the action of spring 126 until the cotter pin 139 is received in recess 140.

Each "inboard" cap 104 is provided with a bayonet-

like projection 141 at one side which is slidably fitted in the bayonet slot 120 of the opposing screen housing. In this manner the "inboard" cap 104 at one end of screen housing 102 supports housing 102 for sliding movement relative to housing 103 by engagement of its bayonet projection 141 in bayonet slot 120 of screen housing 103. Similarly the "inboard" cap at the opposite end of screen housing 103 supports housing 103 for sliding movement relative to housing 102 by engagement of its bayonet projection 141 in bayonet slot 120 of screen housing 102.

The end of each housing 102 and 103 remote from the spring housing is provided with an "outboard" cap member 105. Each "outboard" cap is of a width equal to the combined widths of the two housings 102 and 103, and of a height equal to the combined heights of a screen housing 102 or 103 and a corresponding upper frame member 100 or 101 when superimposed on the housing. "Outboard" cap 105 is vertically divided into two sections 142 and 143. The section 142 which is fitted to the end of housing 102 and 103 remote from the spring housing end is inwardly offset adjacent its upper edge from the inner surface to provide a recess 144 to receive the adjacent end of the corresponding upper frame member 100 or 101 which is seated on a shoulder 145. It will be seen that the length of the upper frame members is greater than the length of the screen housings by an amount equal to the depth of recess 144. The inner surface of "outboard" cap 105 is also provided with upper projections 146 and 147 and a lower projection 148. Projections 146, 147 and 148 are inwardly offset from the marginal edge portions of the inner surface of the "outboard" cap and are contoured about their outer side edges to provide receiving shoulders for the end of the screen housing so that when the screen housing is fitted thereabout and butted against the inner surface of the "outboard" cap the outer marginal edges of the screen housing will be flush with the marginal edges of section 142 of the "outboard" cap which lies below the recess 144. The central portion of the inner surface of section 142 below recess 144 is circularly recessed, as indicated at 149, for a depth substantially equal to the depth of recess 144 to receive the end of the rolled screen therein. A central opening 150 in the outer wall of "outboard" cap 105 receives the reduced end 151 of mandrel 124 for rotation therein. The inner face of section 142 is also recessed, to provide a vertical slot 152 between shoulder 145 and the adjacent section 143 which communicates with circular recess 149 and the recess 144 for the section of screen extending from the mandrel to the upper frame member. A bayonet-like projection 153 on the inner face of "outboard" cap section 142 is received in the end of the bayonet slot 120 of the screen housing which is fitted to section 142. Pins 154 through corresponding holes in the walls of the screen housing and the shoulder projections 146, 147 and 148, secure the housing to the "outboard" cap section 142.

The "outboard" cap section 143 serves as an abutment for the adjacent end of the opposing screen housing and its corresponding upper frame member. A stud 155 on the inner surface of section 143 projects into the end of channel 106 of the corresponding upper frame member when the latter is superimposed on its corresponding screen housing to prevent outward movement of the upper frame member from the housing when the screen assembly is telescoped to closed position. A second stud 156 on the inner surface of cap section 143 is received in a complementary recess 157 in the outer face of the adjacent "inboard" cap 104 when the latter is butted against said "outboard" cap section 143 in the closed position of the screen assembly. It will be noted that the bayonet projection 141 of "inboard" cap 104 is inwardly offset from the outer face of the "inboard" cap 104 to position said bayonet projection 141 inwardly of the bayonet projection 153 on the inner face of "outboard" cap

section 142 when the screen assembly is in the closed position.

The bottom and lower side edges of "outboard" cap 105 are recessed, as indicated at 158, to receive a U-shaped spring member 159, the latter being secured thereto by screws 159a in the bottom of the cap. The side arms of spring 159 are normally biased away from the side edges of the "outboard" cap and are compressed between the sash parting strip and inside stop strip of the sash frame to secure the screen housings at the base of the window frame against any upward force applied. It will be noted that the outer ends of spring member 159 tend to be projected outwardly by the biasing action of the spring member to engage the opposing surfaces of the parting and stop strips of a window frame to prevent upward movement of the screen housings in the window frame. The side edge of recess 158 and spring 159 are tapered at 159b to facilitate fitting of the cap and spring in the window frame.

In Figs. 21 to 24 I have illustrated a further modification of my screen assembly, including upper frame members 160 and 161, screen housings 162, and 163 formed of rolled sheet metal and modified "inboard" and "outboard" cap members 164 and 165.

Upper frame members 160 and 161 are formed from a sheet metal blank rolled to provide top and bottom walls 166 and 167 and inner and outer side walls 168 and 169 in which the tops 166 are provided with longitudinal dove-tail grooves 170 respectively. The inner side walls 168 of frames 160 and 161 are rolled to form interlocking grooves and tongues 171 and 171a respectively for sliding movement of the one frame relative to the other. The free ends of each sheet are overlapped adjacent the juncture of the bottom and inner side walls 167 and 168 with an extension of each inner wall 168 being bent inwardly and then outwardly upon itself to form an inner side recess 172 adjacent the bottom to receive the upper marginal edge of the screen. The screen is held in said recess 172 by pressing the side walls of the recess together.

When the upper frame members 160 and 161 are interlocked U-shaped clips 173 similar to holding clips 108 are slidably arranged thereon by means of dove-tail projections 174 on the under side of the clips which are slidable in the dove-tail grooves 170 in the top walls 166 respectively of said upper frame members.

The screen housings 162 and 163 are each formed from a sheet metal blank rolled to provide a top, an outside and a bottom wall. The inner edge of the top wall is bent to provide an inturned lip 175. The bottom wall 50 of each housing has an upward extension 176 at its inner end which is provided with a longitudinally extending dove-tail groove 177. The inturned lips 175 are inclined to provide a smooth sliding surface for the screens passing therebetween. These inturned portions 175 are inwardly offset from the upturned extensions 176 to provide sufficient clearance for the screens between the housings when the latter are disposed in face-to-face relation.

The "inboard" caps 164 differ from caps 104 in certain details. A continuous projection 180 extends inwardly from the rectangular outer walls 179 about which the inner surfaces of the housing walls are fitted. Studs 181 are provided on the outer surfaces of projection 180 which are received in suitable openings in the housing walls. These studs have a cam surface 182 (see Fig. 25) to permit the housing to be slidably fitted over the projection 180 until the studs are aligned with the openings in the housing walls. One side face of projection 180 is suitably recessed at 183 for slidable fitting of the housing upward extension 176 with its dove-tail shaped member 177. Beyond recess 183 is an interlocking dove-tail projection 184 which is received in the dove-tail groove 177 of the opposing housing to permit sliding movement of the one housing relative to the other.

Projection 180 is recessed, as indicated at 185 to receive a spring housing 186 for rotation therein. The

spring housing is welded or otherwise secured to a screen mandrel 187 for rotation with said mandrel. Mandrel 187 and the spring housing 186 are supported for rotation by a bearing plate 188 in the screen housing, said plate having an opening 189 through which the mandrel extends and is supported for rotation. A coil spring 190 is connected at one end to the adjacent end of mandrel 187 and at the other end to a ratchet disc 191 which engages a ratchet cam surface 192 on the inner end of recess 185. Disc 191 is provided with a slot 193 which is aligned with an opening 194 in the outer wall 179 of cap 164, through which a winding instrument is inserted into slot 193 for applying tension to spring 190.

The "outboard" caps 165 differ from caps 105 in the following respects. A continuous projection 195 extends inwardly from the section of the cap about which the screen housing is fitted over studs 181. The inner side face of projection 195 has a shoulder projection 196 about which member 176 is fitted below the dove-tail shaped member 177. Projection 195 is centrally recessed, at 197, which recess extends well into the main body of cap 165 to receive the rolled screen and mandrel. The outer end of the mandrel is received in an opening (not shown but similar to that shown in Fig. 20) in the outer wall of the cap. The other thickened section of cap 165 is provided with upper and lower bosses 155 and 156 which are received in the ends of the upper frame members and "inboard" caps respectively.

In Figs. 26 to 28, I have shown a variation of the housings and end caps therefor, as illustrated in Figs. 21 to 24. The upturned projection 176 of one housing is unaltered while the upturned projection 176a of the other is shaped to provide a dove-tail 177a which interlocks with the dove-tail groove 177 of the first for sliding movement of one housing relative to the other. The "inboard" cap 164 is grooved or recessed, as illustrated particularly in Fig. 27, so that the dove-tail groove member 177, when received in recess section 183 is stopped from sliding movement relative to the cap while the dove-tail member 177a is permitted to slide through recess section 183a. The "outboard" cap 165 differs in that there is no shoulder projection 196 for support of the upward projection 176 of the housing. A dove-tail member, similar to member 184 shown in Fig. 21, may be substituted for shoulder 196 if it is desired. However, in this event the "outboard" caps at each end of the screen would not be interchangeable.

Fig. 29 illustrates a further modification in the interlock of housings. The male dove-tail extension 176a has a marginal lip 176x which overlaps the upper marginal edge of the female dove-tail extension 176.

Figs. 30 to 33 inclusive, illustrate a further variation of the rolled sheet metal upper frame members and screen housings. The interlocking of the upper frames with each other and with the window sash clip is effected with male and female tongue and groove members 200 which are spot welded or otherwise secured along the surfaces of the frame members and clip. Similarly the interlock between the housings is effected by complementary tongue and groove members indicated generally at 200 which are welded or otherwise secured along the outer surface of the upturned projections 176. As the dove-tail members are secured to project beyond the outer surface of projections 176, the recess 183 in the face of "inboard" cap 164 need only be of a depth equal to the thickness of member 176.

Fig. 34 illustrates a further variation of the screen housing interlocking arrangement. It will be seen that the upward projections 176 have inwardly directed marginal flanges 201 which are received in complementary slots in members 164 extending from the recesses 183. Cap 164 also has an interlock member 203 which projects outwardly, downwardly and then inwardly to receive the marginal flange 201 of the opposing housing in sliding relation. Thus the opposing housings are interlocked

for sliding movement in their longitudinal direction. The inner side edge of projection 195 of the "outboard" cap 165 is recessed at 204 to slidably receive the interlock member 203 of the "inboard" cap 164 when the latter is butted against the outboard cap.

Fig. 35 illustrates a further modification in the rolled sheet metal type upper frame members and in the sash frame clip member. The upper frame members 160 and 161 are provided with oppositely directed side flanges 205 adjacent their upper surfaces. The marginal portions of the sheet are arranged in overlapping relation to provide a double thickness inner side wall 206 between which the upper end of a screen is introduced. The screen is held between said overlapping marginal portions by any suitable means, for example by riveting as indicated at 207. Clip member is moulded or diecast to provide a bridging section 208 and two side members 209 and 210. The underside of bridging section is provided with two inwardly projecting lugs 211 which underlie the outer flanges 205 of each frame member 160 and 161. A T-shaped lug 212 projects downwardly of the centre of the bridging section 208 to underlie the opposing inner flanges 205 of each frame member. The upper surface of bridging section 208 is provided with a series of projections 214 of successively increasing height and having inclined surfaces which correspond with the incline of the undersurface of a sash frame bottom rail. A screw clamp 215, threaded through side member 210, engages one side of a sash rail to grip said rail between the opposing side member 209 and said screw clamp.

This is a continuation in part of my co-pending application Serial No. 102,175, filed June 30, 1949, for Adjustable Window Screen, now abandoned.

I claim:

1. A screen construction for sash type windows, comprising a pair of upper frame members arranged in opposed side by side relation and united along their adjacent side edges for sliding endwise adjustment relative to one another, a pair of screen housing members arranged in opposed side by side relation and united along their adjacent side edges for sliding endwise adjustment relative to one another in cooperation with the corresponding upper frame members, a screening strip secured at one end to one of said upper frame members and at its other end to the corresponding housing member and a second screening strip normally disposed in overlapping relation with said first strip and secured at one end to the remaining upper frame member and at its other end to the remaining corresponding housing member, and roller means mounted in said housings for separately reeling and unreeling said screening strips to facilitate adjustment as to height of said screening strips.

2. A screen construction as set forth in claim 1, in which each of the pair of frame members and each of the pair of housing members is united to its companion member by a dove-tail structure comprising a dove-tail groove throughout the length of the inner side wall of each member and a double-ended dove-tail connector secured by one end thereof in and adjacent the inner end of the groove of each of said members and the other end of each connector slidably fitting in the groove of the opposing member, endwise extension of said members being limited by abutment of said connectors at their inner ends, at least a portion of said screening strips being maintained in overlapping relation by the inter-abutment of said connectors.

3. A screen construction as set forth in claim 1, in which said upper frame members and said housing members are provided with opposed side openings in their adjacent side walls through which the ends of the screens are inserted for securing to said members, each of said frame and housing members having one wall adjacent said side wall recessed adjacent said side opening to receive the screen therein, the adjacent surfaces of the over-

11

lapping portions of said screening strips being slightly spaced from each other to prevent frictional contact between their adjacent surfaces during lateral adjustment of said screen construction.

4. A screen construction as set forth in claim 1, including locking means carried by the outer end of each housing member and engageable with the adjacent end of the corresponding upper frame member to prevent vertical separation therefrom when the screen construction is in its collapsed position.

5. A screen construction as set forth in claim 1, including an end wall removably mounted on the outer end of one of said housings and a corresponding end wall removably mounted on the opposite end of the other housing, means securing said end wall to said housing and locking means carried by said end wall and adapted to engage the adjacent end of the corresponding frame to prevent vertical separation of said frame and housing when the screen is in its closed position.

6. A screen construction as set forth in claim 5, said locking means including dove-tail tongues carried by the said frame members and dove-tail grooves in the upper edge of said end wall interlockable with the dove-tail tongues of the frame members.

7. A screen construction as set forth in claim 5, said end wall being provided with a laterally extending clamping member clampable to a sash guide rail of a window frame.

8. A screen construction as set forth in claim 5, in which each of said end walls is provided with extension members adapted to be butted against the adjacent ends of the opposing upper frame and housing members.

9. A screen construction as set forth in claim 5, said housing being provided with stud receiving recesses in the end face and with pin receiving recesses in opposite sides adjacent said end face, said end wall being provided with side openings aligned with the housing pin receiving recesses and said means for securing the end wall to the housing comprising positioning studs on the inner surface of said end wall fitted in the corresponding stud receiving recesses in the housing and a plurality of pin members inserted through said side openings provided in the end wall to engage in the pin receiving recesses of the housing in locking engagement, at least one of said studs being recessed to receive a portion of a pin member in locking engagement therewith.

10. A screen construction as set forth in claim 1, in which each of said frame members and each of said housing members is united to its companion member by interlocking connectors comprising a male connector carried by one of said members and a cooperating female portion carried by the opposing corresponding member, said connector and portion being interlocked for sliding movement of each member relative to the corresponding member to provide endwise extension of said members.

11. A screen construction as set forth in claim 1, in which said housing members are provided with side openings in their adjacent side walls through which the ends of the screens are inserted for securing to said housings, each of said housings having the side edge of one wall adjacent said side wall inwardly offset with respect to

12

the side edge of the corresponding wall of the companion housing for passage of the screens therebetween with the adjacent surfaces of the overlapping portions of said screening strips being slightly spaced from each other to prevent frictional contact between their adjacent surfaces during lateral adjustment of said screen construction.

12. A screen construction as set forth in claim 1, including an outer end wall removably mounted on the outer end of one of said housing members and a corresponding outer end wall removably mounted on the opposite outer end of the companion housing member, means securing each of said end walls to its complementary housing member, said end walls being provided with an upwardly directed extension against which the adjacent end of the corresponding upper frame member is butted and a laterally directed extension against which the adjacent ends of the companion housing member and its corresponding upper frame member are butted when the screen construction is in its collapsed position.

13. A screen construction as set forth in claim 12, in which said outer end walls are provided at opposite sides with divergent compression members compressible to engage the inner surfaces of opposing guide rails for a sash frame to retain said end walls against sliding movement relative to the frame.

14. A screen construction as set forth in claim 12, including an inner end wall removably mounted on the inner end of one of said housings and a corresponding inner end wall removably mounted on the inner end of the other housing, means securing each of said inner end walls to its complementary housing, each of said inner end walls being butted against said side extension of the outer end wall of the opposing housing when the screen construction is collapsed, and locking means carried by each of said extensions to engage the adjacent inner end wall for limiting the latter to endwise movement.

15. A screen construction as set forth in claim 12, including means for separately interlocking said companion housing member and its corresponding upper frame member with said laterally directed extension when they are in face-to-face relation, said means comprising a lateral projection from the face of the one, said projection being received in the opposing face of the other to prevent vertical separation between said companion housing member and its corresponding frame member relative to said extension when the screen construction is collapsed.
